CLAIM

The ornamental design for a taxi motor vehicle, as shown and described.

DESCRIPTION

1.1 is a perspective view of a taxi motor vehicle showing our new design;

1.2 is a front elevation view thereof;

1.3 is a rear elevation view thereof;

1.4 is a top plan view thereof;

1.5 is a right side elevation view thereof; and

1.6 is a left side elevation view thereof.

The broken lines represent portions of the taxi motor vehicle that do not form a part of the claimed design.
